UNITED STATES PATENT OFFICE.

PERCY K. BARKER, OF CLEVELAND, OHIO, ASSIGNOR, BY MESNE ASSIGNMENTS, OF ONE-HALF TO ARTHUR R. BETZ, OF SHAKER HEIGHTS VILLAGE, OHIO.

DISHWASHING MACHINE.

Application filed December 17, 1921. Serial No. 222,117.

This invention relates to improvements in the dishes for drying the same, as will appear later.

The objects of this invention are to provide a dish washing machine in which the dishes can be washed, rinsed and dried, with the same form and structure as here illustrated, this frame being covered with rubber by dipping the same into a rubber composition. This rack, as viewed in Fig. 3, comprises the marginal strands 7, the intermediate strands 8, and a plurality of transversely extending strands 9 of a configuration resembling an inverted V, indicated at 9, between the marginal and intermediate strands. The middle portions of the transverse strands are substantially horizontal as indicated at 10. This rack is supported upon the trough member 12 which in turn is suitably secured upon the upstanding projections 13 which are cast integrally at the bottom of the lower casing member. The trough member is notched, as indicated at 15, for the seating of the lower transverse portions of the rack, as clearly indicated in Figs. 3 and 4.

In the bottom of the trough member, which is open entirely throughout its top, is provided the comparatively restricted slot 16 for passage therethrough of the vapor or air which is set in circulation by the suction fan. One of the upstanding projections 13 is also provided with an opening 17 forming part of the passage for the vapor or air which is forced through the opening 16.

The vapor or air is forced through the conduit which is formed by the complementary conduit sections provided in the upper and lower casing members and which are adapted for registry with each other upon assembly of the upper and lower parts of the casing. The lower conduit is indicated at 18 while the conduit in the upper casing member is indicated at 19; and it will be noted that the lower conduit has connection through the opening 17. It is noted also that the rack is provided with suitably formed extensions 7' about the two sides of the conduit 18 so that the conduit in the lower casing member will not interfere with the seating of the rack.

The casing in the present device comprises the substantially elliptical members 1 and 2 which are seated one upon the other by means of the flange 3 depending from the upper member into the correspondingly formed channel 4 around the lower member. The rubber gasket 3' forms an air-tight joint and the particular shape of casing adapts it to seat in the ordinary kitchen sink or on the drain board. The lower member is provided with a rack for holding the dishes while the upper member is provided with a motor driven fan, preferably a suction fan, for effecting circulation of vapor or air through the water in the lower member during the washing operation, as well as during the rinsing operation if so desired, and later for effecting circulation of outside air over

The upper casing member is provided with an opening 20 through the top thereof which is closed by means of an electric motor 21 whose base is secured in any suitable manner over the opening 20, the motor resting upon

the top of the casing. The fan 22 is supported upon the rotor shaft of the motor for operation thereby. The integrally formed auxiliary casing 23 surrounding the fan is of a substantially convolute form and merges into the conduit 24 which has communication with the conduit 19. A circular guard plate 25 is secured by means of bolts 26 and spacers 27 in spaced relation to the under face of the auxiliary casing, the purpose of this guard plate being to protect the fan from the water in the lower part of the casing. The plate 25 is perforated, however, as indicated at 28, so as to permit the passage of vapor or air therethrough as it is sucked by the fan up through the casing. The bottom of the auxiliary casing 23 is provided with the circular opening 29. The perforations in the plate 25 also permit the draining of any water that might be splashed thereonto.

On one side and at the upper corner portion of the upper part of the casing I have provided the detachable deflector cap 30 which is secured in position on the casing by means of the bail 31 pivoted to the casing member at 32 and adapted to engage over the projection 33 provided on the cap. This deflector cap forms an intermediate part of the conduit which comprises the conduit sections 24 and 19, so that when the deflector cap is secured in position, as shown in Fig. 3, continuous passage is provided for the vapor or air. This deflector cap is secured in such position during the washing operation as well as the rinsing operation, if so desired, so that the warm air and steam from the water in the casing will be sucked up by the fan. Atmospheric pressure through the opening 35 causes this vapor and steam to be forced up through the wash water, a vacuum having been created above the wash water by the fan. Thus the heat of the water is conserved. When, however, it is desired to dry the dishes, the deflector cap is removed so that outside, comparatively dry air will by virtue of its atmospheric pressure pass through the duct 19, which is now open to the atmosphere, and be drawn up through the casing by the vacuum created by the fan; while the air after being used will be discharged from the duct 24 to the outside atmosphere. The opening 35 may be used also as a means of filling the casing with water to the level indicated in Fig. 4, or it can be filled by attaching a discharge tube connected at one end to outlet 36 and at its other end to a source at sufficient elevation.

60 Thus the dishes are placed upon the rack in the manner indicated in skeleton form in Fig. 3, the plates resting upon the intermediate strands 8 between the strands 9. Water is then supplied to the casing to the proper level. With the deflector cap 30 se-

cured in position, the warm air and steam will be sucked up by the fan, thereby creating a vacuum above the water, the atmospheric pressure through opening 35 causing circulation of such vapor through the casing 70 so as to cause agitation and aeration of the water. The passage of air up through the restricted slot in the bottom of the trough member forces the water up out of the trough, whereupon the water from the 75 sides of the casing rushes in to again fill the trough. Thus the water is swished from side to side and is spouted intermittently upwardly as the trough is alternately emptied and filled. Upon completion of the wash- 80 ing operation the wash water is drained through the discharge outlet 36, provided with a suitable closure 37. Running of the fan during the draining operation will continue to agitate the water until it is all discharged, and thus the grease and dirt suspended in the water is prevented from depositing in the casing. The dishes are then rinsed, with or without the fan, preparatory to drying. In order to circulate fresh and 90 comparatively dry air over the dishes, the deflector cap 30 is removed so that outside air is drawn into the lower part of the casing and discharges through the conduit 24. 95

What I claim is:

1. A dish washing machine, comprising upper and lower casing members, the walls of which enclose a chamber, means in the chamber of the lower casing member for supporting the dishes, means within the chamber of the upper casing member for effecting circulation of vapor or air through said casing members, and a circulation conduit lying within the walls of said casing 100 and extending from the upper part of the upper casing member to the lower part of the lower casing member.

2. A dish washing machine comprising a casing for holding dishes, means in the upper part thereof for withdrawing air from the upper part of the casing, and a conduit communicating with the discharge side of said means and open to atmosphere and communicating with the lower part of the casing 110 for the passage of vapor or air therethrough.

3. A dish washing machine comprising upper and lower casing members, means in the lower casing member for supporting dishes, means in the upper casing member for effecting circulation of vapor or air through said casing members, and a conduit open to atmosphere and extending from said means to a point in the bottom part of the casing, thereby causing vapor or air 120 to be circulated up through the same.

4. A dish washing machine comprising upper and lower sections, means for forming an air-tight joint between said sections in assembly, means for withdrawing air 125

from the upper part of the casing, and a discharge conduit for said means open to atmosphere and communicating with the lower part of the casing for the passage of vapor or air therethrough.

5. A dish washing machine comprising a casing for holding dishes, means in the upper part of said casing for effecting circulation of vapor from above the washing fluid 10 through the casing during the washing operation, including a conduit leading to the lower part of said casing, and a detachable deflector cap forming part of said conduit, whereby upon removal of said cap outside 15 air can be circulated through the casing.

6. A dish washing machine comprising upper and lower casing members, means in the lower casing member for supporting dishes, means in the upper casing member 20 for effecting circulation of vapor or air through said casing members, said casing members being provided with registering conduits for such circulation from the top of said upper casing member to the lower 25 part of said lower casing member.

7: A dish washing machine comprising upper and lower casing members, means in the lower casing member for supporting dishes, means in the upper casing member 30 for effecting circulation of vapor or air through said casing members, said casing members being provided with registering conduits for such circulation from the top of said upper casing member to the lower part 35 of said lower casing member, the conduit in said lower casing member terminating in a

restricted opening for passage of air up through the casing.

8. A dish washing machine comprising a casing, a trough member in the lower portion thereof, said trough member being provided with a slot through its bottom communicating with a source of air supply, and means in the upper part of the casing for effecting circulation of vapor or air through 45 said slot so as to pass up through the casing.

9. A dish washing machine, comprising a casing, a trough member in the lower portion thereof, a dish rack removably supported upon said trough member, said trough 50 member being provided with a slot through its bottom communicating with a source of air supply, and means in the upper part of the casing for effecting circulation of vapor or air through said slot so as to pass up 55 through the casing.

10. A dish washing machine comprising a casing for holding dishes, means in the upper part of said casing for effecting circulation of vapor from above the washing fluid 60 through the casing during the washing operation, including a conduit leading to the lower part of said casing, and a detachable deflector cap forming part of said conduit, whereby upon removal of said cap 65 outside air can be circulated through the casing, said cap being provided with an opening to atmosphere.

In testimony whereof I hereby affix my signature.

PERCY E. BARKER.
